SPRING CONSTRUCTION

Gordon J. Birgbauer, Sr., Grosse Pointe Woods, Mich., assignor, by mesne assignments, to American Metal Products Company, Detroit, Mich., a corporation of Michigan

Filed Jan. 11, 1963, Ser. No. 250,853

8 Claims. (Cl. 5—247)

This invention relates to a spring construction, and more particularly to a device of this type comprising a frame, a sinuous type spring formed of a plurality of spring strips, and a support for the spring strips to prevent excessive or undue sagging thereof.

More particularly this invention relates to a spring construction in which the spring surface comprises a plurality of strips extending between spaced frame members and a primary object of the invention is to provide a support for the spring strips spanning the spring strips intermediate the ends thereof to brace or support the spring strips against excessive sagging when the spring surface is occupied.

Another object of the invention is to provide a support of this type which approaches the ultimate in structural simplicity and comprises one or more nonextensible rod-like members which extend transversely of the spring strips intermediate their ends to add stability thereto and to prevent undue sagging when the spring surface is in use.

If the invention is employed in connection with a spring construction used in a bed, the frame is usually rectangular and comprises a pair of spaced side frame members connected by a pair of end frame members. The spring surface is formed of a plurality of spring strips extending between the side frame members and having their ends connected thereto. The supporting means of this invention consists of one or more, preferably two, nonextensible rod-like members connected at their ends to the end frame members and extending transversely of said spring strips and interwoven therewith to alternately engage the tops and bottoms of adjacent spring strips or multiples of spring strips, to support the spring strips intermediate their length against undue sagging. Thus, with this invention, long spans of spring strips may be employed and supported against excessive sagging when the spring surface is occupied.

This invention may be useful in connection with all types of spring constructions but finds particularly utility when used in connection with spring surfaces comprising a plurality of spring strips each formed by sinuously bending a suitable spring wire into adjacent oppositely disposed loops joined together by straight portions such as shown in the patent to Karl Kaden, Reissue 21,263.

The various objects and advantages and the novel details of construction of one commercially practical embodiment of the invention will become more apparent as this description proceeds, especially when considered in connection with the accompanying drawings, in which:

FIGURE 1 is a plan view of a spring construction showing the invention, certain parts being fragmentarily illustrated;

FIGURE 2 is a longitudinal section taken substantially on the plane indicated by line 2—2 in FIGURE 1;

FIGURE 3 is an enlarged fragmentary plan view of the portion of FIGURE 1 enclosed by the line A;

FIGURE 4 is an enlarged fragmentary sectional view taken substantially on the plane indicated by line 4—4 in FIGURE 1; and

FIGURE 5 is a fragmentary elevational view of a corner of the frame member before the same is bent into shape.

2

The present invention will be described as employed in connection with a bed frame spring construction, although it will be obvious as this description proceeds that it may be used with equal facility in other types of spring constructions.

In FIGURE 1 of the drawings, the frame member 10 is shown as being substantially rectangular in plan view and comprises a pair of side frame members 11 arranged in spaced relation to one another and connected by end frame members 12. The frame members 11 and 12 may conveniently be formed of angle irons, as shown in FIGURES 2 and 4.

The frame 10 may conveniently be formed of two longitudinal integral halves which have their confronting end edges welded together as at 13. The corners 14 of each longitudinal half section of the frame may be formed by cutting away the upper web of the angle iron member, as shown in FIGURE 5, to form beveled or chamfered edge ends 15, and further cutting away of the flange of the angle iron to form curved surfaces 16. Thus, at each corner remaining vertical web portion 17 may be bent until the beveled or chamfered edges 15 abut, whereupon the adjacent portions of the angle iron will extend at right angles to one another and these beveled or chamfered edges may then be welded as at 18, as shown in FIGURES 1 and 3 to form the integral half sections.

The spring surface 20 of the device is formed of a plurality of spring strips 21, each formed by sinuously bending a suitable spring wire into oppositely disposed loops 22 and 23 which are joined together by straight portions 24. Each end of each spring strip 21 is provided with a hooked end 25 adapted to engage an aperture 26 in the side frame member 11. At spaced points, the opposed adjacent loops 23—23 may be connected by wire links or spacer clips 27 to interconnect and properly locate the spring strips 21. The spring strips 21 at the ends of the spring surface 20 are connected to the end frame members 12 by means of coil springs 28 having one end 29 hooked around an adjacent loop of the adjacent spring strip and the other end 30 engaging an aperture 31 in the end frame member 12.

In order to lend rigidity to the frame 10, one or more, here shown as two, transverse braces 35 may be provided. These braces 35 extend transversely of the frame 10 between the side frame members 11 and have their ends 35a welded to the latter. Apertures 37 may be employed for attaching legs (not shown) in the frame 10.

The spring strips, while being formed, may be coiled on an arc of small diameter, as described in the aforesaid patent, Re. 21,263, which will apply a set or curvature to the spring strips. In applying the spring strips to the frame 10, the hooked ends 25 of the spring strips 21 are engaged in the apertures 26 along one side frame member 11 and the springs are then stretched until the other hooked ends can be engaged with the apertures 26 in the opposite frame member 11.

In beds or the like, it is necessary to use comparatively long lengths of spring strips to span the space between the side frame members 11. With this invention, long spans of spring strips may be safely employed and supported against excessive sagging when the spring surface 20 is occupied.

In accordance with this invention, there is provided an intermediate support for the spring strips which consists of one or more, here shown as two, rod-like members 40 provided at each end with hook-like portions 41 adapted to engage apertures 42 formed in the end frame members 12. These supporting members 40 are nonextensible, but they may be slightly longitudinally flexible. These rod-like members 40 extend transversely of the spring strips 21 intermediate the ends thereof and preferably

adjacent the longitudinal center of the spring surface 20. The supporting members 40 are interwoven or interlaced with the spring strips 21 so as to alternately engage the top and bottom surfaces of certain of the spring strips. As shown in FIGURE 1, one preferred arrangement is to have the supporting members 40 alternately engage the tops of one pair of spring strips 21 and the bottoms of the next adjacent pair of spring strips 21, although, obviously, the supporting members 40 may engage the tops and bottoms of adjacent spring strips or any other multiples of adjacent spring strips.

With the above described construction, the spring surface 20 is stabilized and the spring strips 21 are supported intermediate their ends so as to brace the same against excessive displacement when the spring surface is occupied. As stated, the rod-like members or supports 40 are substantially nonextensible, but they may be slightly longitudinally flexible.

The described construction provides a simple but effective means for accomplishing the purposes of the invention.

While one commercially practical embodiment of the invention has been described and illustrated herein somewhat in detail, it will be understood that various changes may be made as may come within the purview of the accompanying claims.

What is claimed is:

1. In a spring construction having a rigid frame and a spring device including a plurality of extensible spring strips connected at their ends to said frame, that improvement which comprises, a non-extensible supporting member extending transversely of said spring strips and connected at its ends to said rigid frame, said member being solely supported by said frame and providing the sole support for the center of said spring strips against excessive displacement.

2. In a spring construction having a rigid frame and a spring device including a plurality of extensible spring strips connected at their ends to said frame, that improvement which comprises, a substantially nonextensible supporting member extending transversely of said spring strips and engaging the underside of some of said spring strips, and means connecting the ends of said supporting member to said rigid frame, said member being supported by said rigid frame and providing the sole support for the center of said spring strips against excessive displacement.

3. In a spring construction having a rigid frame and a spring device including a plurality of extensible spring strips connected at their ends to said frame, that improvement which comprises, a nonextensible supporting member extending transversely of said spring strips alternately above and below certain of said spring strips, and means connecting the ends of said supporting member to said rigid frame, said member being solely supported by said rigid frame and providing the sole support for the center of said spring strips against excessive displacement.

4. In a spring construction having a rigid frame and a spring device including a plurality of extensible spring strips connected at their ends to said frame, that improvement which comprises, a longitudinally flexible, nonextensible supporting member extending transversely of said spring strips alternately above and below adjacent pairs of said spring strips, and means connecting the ends of said supporting member to said rigid frame, said member

being supported solely by said rigid frame and providing the sole support for the center of said spring strips against excessive displacement.

5. A spring construction comprising, a rigid frame, a plurality of extensible spring strips extending across and connected to said frame in spaced relation to one another, and an intermediate support for said spring strips comprising a substantially nonextensible member extending transversely of said spring strips and connected at its ends to said rigid frame, said member being supported solely by said rigid frame and providing the sole support for the center of said spring strips against excessive displacement.

6. A spring construction comprising, a rigid frame, a spring surface comprising a plurality of spring strips each formed by sinuously bending a spring wire into adjacent oppositely disposed loops, said spring strips extending across and connected to said frame in spaced relation to one another, and a substantially nonextensible supporting member connected to said rigid frame and extending transversely of said spring strips and interwoven therewith to alternately engage the top and bottom surfaces of certain of said spring strips to provide the sole support for the center of the same against excessive displacement when the spring surface is occupied.

7. A spring construction comprising, a substantially rectangular rigid frame, a plurality of spring strips each formed by sinuously bending a spring wire into adjacent oppositely disposed loops, said spring strips extending across and having their ends connected to said frame in spaced relation to one another, and a substantially nonextensible supporting member having its ends connected to said rigid frame and extending at right angles to said spring strips and interlaced therewith to alternately engage the top and bottom surfaces of certain of said spring strips to be the sole support for the center of the same against undue sagging.

8. A spring construction comprising, a rigid frame having a pair of spaced side frame members connected at their ends by a pair of end frame members, a spring surface comprising a plurality of spring strips each formed by sinuously bending a spring wire into adjacent oppositely disposed loops, said spring strips extending between said side rigid frame members in spaced relation to one another and having their ends connected to said side frame members, and an intermediate support for said spring strips comprising a plurality of rod-like members having their ends connected to said end frame members and extending transversely of said spring strips and interlaced therewith to alternately extend above and below certain of said spring strips to be the sole support for the center of said spring surface against excessive sagging.
